CLAIM

The ornamental design for a hail guard, as shown and described.

DESCRIPTION

FIG. 1 is an isometric view of the hail guard of the invention; FIG. 2 is an end view of the hail guard of the invention; FIG. 3 is an end view of the hail guard of the invention opposite that of FIG. 2;

FIG. 4 is a side view of the hail guard of the invention; FIG. 5 is a top plan view of the hail guard of the invention; FIG. 6 is a bottom plan view of the hail guard of the invention; and,

FIG. 7 is a side view of the hail guard of the invention opposite that of FIG. 4.

The broken line showing of environment is for illustrative purposes only and forms no part of the claimed design.
